(57) **CLAIM**

The ornamental design for an apparatus for securing a walking assist device as shown and described.

DESCRIPTION

FIG. 1 is a top perspective view of an apparatus for securing a walking assist device, according to a first embodiment; FIG. 2 is a rear elevation view of the apparatus of FIG. 1; FIG. 3 is a front elevation view of the apparatus of FIG. 1; FIG. 4 is a right side elevation view of the apparatus of FIG. 1;

FIG. 5 is a left side elevation view of the apparatus of FIG. 1;

FIG. 6 is a top view of the apparatus of FIG. 1;

FIG. 7 is a bottom view of the apparatus of FIG. 1;

FIG. 8 is a top perspective view of an apparatus for securing a walking assist device, according to a second embodiment; FIG. 9 is a rear elevation view of the apparatus of FIG. 8; FIG. 10 is a front elevation view of the apparatus of FIG. 8; FIG. 11 is a right side elevation view of the apparatus of FIG. 8;

FIG. 12 is a left side elevation view of the apparatus of FIG. 8;

FIG. 13 is a top view of the apparatus of FIG. 8; and,

FIG. 14 is a bottom view of the apparatus of FIG. 8.
